UNITED STATES PATENT OFFICE.

HORATIO SMITH, OF KIDDERMINSTER, ENGLAND, ASSIGNOR TO WILLIAM MANSELL DAINTREY, OF NEW YORK, N. Y.

DESIGN FOR A CARPET.

SPECIFICATION forming part of Design No. 12,945, dated May 23, 1882.

Application filed March 14, 1882. Term of patent 3½ years. Patented in England November 27, 1881, No. 374,767.

To all whom it may concern:

Be it known that I, HORATIO SMITH, of Kidderminster, England, have invented a new and original Design for Carpets, of which the following is a specification.

This invention relates to a new and original design for carpets and similar fabrics; and it consists in the novel grouping and configuration of parts hereinafter more fully described.

10 The accompanying photograph illustrates a face view of a carpet having my new design.

The stripe A contains ornamentation consisting of the series of figures *d*, resembling arches supported by pillars at the sides, each 15 arch containing within it a rectangular throne-like figure. From the top of each alternate arch springs a rose-like flower, *a*, and behind these flowers runs a band ornamented with a series of circular figures.

20 The stripe B contains the branch *f*, bearing oblong leaves on each side of a central stem, also the branch *e*, having a central stem bearing oblong leaves and two large rose-like flowers and circular buds at and near its end.

25 These branches *e* run across a background composed of parallelograms, showing various designs of checkered and mosaic-like figures.

These figures composing the background are described and claimed in an application for a Design Patent filed by me March 14, 1882, Serial No. 55,303, and therefore I do not here claim them.

The band C contains a series of parallel lines, between which runs a series of semicircular figures.

I claim—

1. The design for carpets, consisting of the stripe A, containing figures *a*, *b*, and *d*, substantially as shown.

2. The design for carpets, consisting of the figure *e*, substantially as shown.

3. The design for carpets, consisting of the stripe B, containing figures *e* and *f*, substantially as shown.

4. The design for carpets, consisting of the stripe A, containing figures *a* *b* *d*, stripe B, containing figures *e* and *f*, and band C, substantially as shown.

The foregoing specification of my invention signed by me this 30th day of November, 1881. 50

HORATIO SMITH.
